(57) **CLAIM**

The ornamental design for a fender air vent, as shown and described.

DESCRIPTION

FIG. 1 is a front perspective view or a fender air vent showing our new design;

FIG. 2 is a front view thereof;

FIG. 3 is a rear view thereof;

FIG. 4 is a side view thereof;

FIG. 5 is a top view thereof; and,

FIG. 6 is a bottom view thereof.

The broken lines illustrate portions of the fender air vent that form no part of claimed design.

1 Claim, 4 Drawing Sheets

FIG. 2

FIG. 3
